(57) **CLAIM**

An ornamental design for the multimedia system game tray, as shown and described.

DESCRIPTION

FIG. 1 is a first perspective view of a design for the multimedia system game tray;

FIG. 2 is a second perspective view of the design therefor;

FIG. 3 is a third perspective view of the design therefor;

FIG. 4 is a first end view of the design therefor;

FIG. 5 is a second end view of the design therefor;

FIG. 6 is a side view of the design therefor mirrored on the opposing side;

FIG. 7 is a top plan view of the design therefor; and,

FIG. 8 is a bottom plan view of the design therefor.

The dashed lines in the drawings are shown for environmental purposes and form no part of the claimed design.
